ATTORNEY

UNITED STATES PATENT OFFICE.

WILLIAM E. GINSBERG, OF BRIDGEPORT, CONNECTICUT.

TOOL-HOLDER.

1,266,249.

Specification of Letters Patent.

Patented May 14, 1918.

Application filed April 25, 1917. Serial No. 164,521.

To all whom it may concern:

Be it known that I, WILLIAM E. GINSBERG, a citizen of the United States, residing at Bridgeport, in the county of Fairfield and State of Connecticut, have invented certain new and useful Improvements in Tool-Holders, of which the following is a specification.

This invention relates to new and useful improvements in lathe tools and the like and the principal object of the invention is to provide a device of this character with means for holding the cutter firmly against movement.

Another object of the invention is to provide simple and efficient means for holding the cutter in the holder, whereby the same can be adjusted.

Another object of the invention is to provide the holder with an off-set portion, whereby the tool will cut close to the shoulder.

Another object is to make the tool with a cutting edge at each end thereof.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings, wherein like characters denote like or corresponding parts throughout the several views, and in which:

Figure 1 is an elevation of one form of the invention.

Fig. 2 is a like view of another form.

Fig. 3 is a plan view of Fig. 1.

Fig. 4 is a plan view of Fig. 2.

Fig. 5 is an end view of Fig. 2.

Fig. 6 is an end view of Fig. 1.

In these figures, 1 indicates the tool holder having an angularly projecting portion 2 and a head 3 connected to the portion 2 so that said head is out of the longitudinal plane of the part 1. This head extends at an angle as shown in Fig. 1 and is provided with a slot 4 provided with teeth 5 and an elongated slot 6. 7 is the cutter provided with a cutting edge at each end thereof and with a projecting portion 8 fitting into the slot 4 and provided with teeth for engaging with the teeth 5 in the bottom of the recess 4. The cutter is held in place by means of the bolt 9 passing through the slot 6 and having screw threaded engagement with the cutter.

By this arrangement, the cutter is firmly held in the desired position by means of the bolt 9 and the teeth. Furthermore, the cutter can be easily removed without taking the holder from the lathe so as to be sharpened and as both ends of the cutter are provided with cutting edges when the cutter at one end is worn the cutter may be reversed so as to use the other end.

In the modification shown in Fig. 2, the invention is shown applied to the well known type of spring holder, the spring being provided by means of the slots 10 in the head and the amount of movement of the spring head being controlled by means of the screws 11. The front end of the head is provided with graduations, as shown at 12, to mark the place which the cutter occupies so that the cutter can be placed in the same position after it has been removed for grinding.

The operation of this tool will be clearly understood by those skilled in the art, and it is of special value in the cutting of the threads on taps, as the cutter can be removed and sharpened and replaced accurately, without removing the holder from its fixed position in the machine.

It is thought from the foregoing that the advantages and novel features of my invention will be readily apparent.

I desire it to be understood that I may make slight changes in the construction and in the combination and arrangement of the

several parts, provided that such changes fall within the scope of the appended claim. 10

I claim as my invention:

A lathe tool comprising a holder having 5 a head, said head having a groove therein and an elongated slot, a cutter having a portion fitting in said groove, teeth on said portion and in the groove engaging with

each other and a screw passing through the slot and engaging with the cutter.

In testimony whereof I affix my signature in presence of two witnesses.

WILLIAM E. GINSBERG.

Witnesses:

Joe J. GINSBERG,
W. E. TAUBERT.
